United States Patent Office

Des. 185,574
Patented June 23, 1959

185,574

CORER OR THE LIKE

Charles P. Schiller, Winter Haven, Fla.

Application May 2, 1958, Serial No. 50,734

Term of patent 14 years

(Cl. D89—1)

The essential features of my design are shown in full lines in the drawings.

I claim:

The ornamental design for a corer or the like, as shown and described.
